UNITED STATES PATENT OFFICE.

THOMAS S. PERKINS, OF IRWIN, PENNSYLVANIA, ASSIGNOR TO WESTINGHOUSE ELECTRIC & MANUFACTURING COMPANY, A CORPORATION OF PENNSYLVANIA.

FUSE.

Application filed March 14, 1918. Serial No. 222,440.

To all whom it may concern:

Be it known that I, THOMAS S. PERKINS, a citizen of the United States, and a resident of Irwin, in the county of Westmoreland and State of Pennsylvania, have invented a new and useful Improvement in Fuses, of which the following is a specification.

My invention relates to fuses for electric circuits and particularly to enclosed fuses embodying a readily renewable fusible element.

One object of my invention is to provide a device of the above-indicated character that shall be simple in construction, efficient in operation, and economical to manufacture.

Another object of my invention is to provide means for so localizing the effects of the rupture of a fusible element as to prevent the complete destruction of the same.

A still further object of my invention is to provide a fusible element of such configuration that, at rupture, the separated portions of the same may be forced apart in predetermined directions.

In practicing my invention, I provide a fusible element, supported only at its ends, that is of such configuration as to utilize the explosive forces generated by the rupture thereof to force the separated portions of the same rapidly apart.

Figure 1 of the accompanying drawings is a longitudinal sectional view of a fuse embodying my invention; Fig. 2 is a view taken along the line II-II of Fig. 1; Fig. 3 is a longitudinal sectional view of a modified form of fuse embodying my invention; Fig. 4 is a fragmentary view of a further modification of my invention, and Figs. 5 and 6 are views, partially in elevation and partially in section, of still further modifications of the same.

In Figs. 1 and 2, a tubular insulating receptacle 1, of fiber or other suitable material, is exteriorly screw-threaded, at its ends, to receive co-operating cap members 2, of copper or other conducting material. Conducting disks 3, disposed at the ends of the receptacle 1 and within the cap members 2, are provided with apertures 4 through which the ends 5 of a fusible element 6 project. The ends 5 of the element 6 are bent to lie between the solid portions 7 of the disks 3 and the cap members 2 in which position

they may be compressed to insure good electrical contact by screwing the cap members 2 inwardly. The element 6 is transversely bent at a constricted mid portion 8 upon either side of which the half-sections 9 and 10 extend in substantially parallel planes. The portion 8, being of smaller cross section than the body of the element, fuses with violence at a predetermined current value and forces the half-sections 9 and 10 laterally and oppositely apart to positions indicated by the broken lines.

To assist the above-described action, the sections 9 and 10 may be oppositely tensioned, or, as shown in Fig. 3, springs 11 may be suitably attached to the disks 3, as by rivets 12, and so extended as to properly bear upon the sections 9 and 10. The separation of the sections 9 and 10 may be effected, as shown in Fig. 4, by the force of the springs 11 only, in which instance, the fusible element will not necessarily be bent, as in Figs. 1, 2 and 3.

In the modification shown in Fig. 5, the fusible element is of Z-shape, and, consequently, where the constricted portion 8 is ruptured, the explosive force is exerted laterally against the relatively wide portions 9 and 10 to force them apart. In Fig. 6, the element 6 is so bent as to constitute portions 13 and 14 having relatively large surfaces at right angles to the portion 8. In this modification, the portions 13 and 14 occupying a relatively large portion of the transverse area of the receptacle 1 are acted upon by the explosion forces to cause the unruptured portions to be forced longitudinally apart.

The sudden separation of the sections 9 and 10, upon rupture of the portion 8, prevents prolongation of a destructive arc and diminishes the amount of flame and gases formed thereby. Thus, the life and efficiency of the device are increased and the danger from fire considerably reduced.

While I have shown and described particular forms of my device, many changes may be effected therein without departing from the spirit and scope thereof, as set forth in the appended claims.

I claim as my invention:

1. Fuse mechanism comprising a tubular receptacle, terminals disposed at opposite ends of and closing the receptacle, and a fusible element for connecting the terminals.

2
and for interrupting the connection under predetermined current conditions comprising a strip of flexible fusible material having a portion of reduced current-carrying capacity extending transversely of the receptacle and longitudinally extending portions connected to the terminals and adapted to be moved laterally in opposite directions by the reactive force of volatilization of the transversely extending portion.

10 2. Fuse mechanism comprising a tubular receptacle, terminals disposed adjacent the ends of and closing the receptacle, and a fusible element for connecting the terminals and for interrupting the connection under predetermined current conditions comprising a pair of flexible conductive elements having their nonadjacent ends connected to separate terminals and their adjacent ends connected by a transversely disposed fusible element having a portion of reduced current-carrying capacity intermediate the points of connection to the conductive elements adapted to rupture and to cause lateral separation 25 of the conductive elements by reason of the reactive force of volatilization of the disrupted portions of the fusible elements.

3. Fuse mechanism comprising a tubular receptacle, terminals disposed at opposite ends of and closing the receptacle, and a fusible element for connecting the terminals and for interrupting the connection under predetermined current conditions comprising a strip of flexible fusible material having a portion of reduced current-carrying capacity extending transversely of the re-

ceptacle and longitudinally extending portions connected to the terminals and adapted to be moved laterally in opposite directions into engagement with the walls of the receptacle when the portion of reduced current-carrying capacity is ruptured.

4. Fuse mechanism comprising a tubular receptacle, terminals disposed at opposite ends of and closing the receptacle, and a fusible element for connecting the terminals and for interrupting the connection under predetermined current conditions comprising a pair of conductive elements normally held in spaced relation to the walls of the receptacle and movable laterally into engagement with the wall of the receptacle when the fusible element is ruptured.

5. Fuse mechanism comprising a tubular receptacle, terminals disposed at opposite ends of and closing the receptacle, and a fusible element for connecting the terminals and for interrupting the connection under predetermined current conditions comprising a pair of conductive laterally movable elements having their nonadjacent ends connected to the terminals and their adjacent ends in overlapped relation and a fusible element connecting the overlapped ends and adapted to rupture at a point between the overlapped ends whereby they will be displaced laterally by the gases of combustion of the fusible element.

In testimony whereof, I have hereunto subscribed my name this 7th day of March, 1918.

THOMAS S. PERKINS.
